ATTYS

UNITED STATES PATENT OFFICE.

WILLIAM B. SHERMAN, OF PROVIDENCE, RHODE ISLAND.

DESIGN FOR A BADGE.

SPECIFICATION forming part of Design No. 34,745, dated July 9, 1901.

Application filed June 10, 1901. Serial No. 64,054. Term of patent 3½ years.

To all whom it may concern:

Be it known that I, WILLIAM B. SHERMAN, a citizen of the United States of America, and a resident of Providence, in the county of Providence and State of Rhode Island, have invented and produced a new and original Design for a Badge, of which the following is a specification.

In the accompanying drawings, Figure 1 represents a front or face view of a badge embodying my design, and Fig. 2 is a side view of the same.

The leading feature of my design consists of the representation of the head of an American buffalo or bison and a flag located at the top of and partly concealed by the said head.

As shown in the drawings, A designates the head of an American buffalo, and B a flag,

which is arranged at the back of the head and partly concealed by it, the ends of the flag extending beyond the head in a lateral direction. The flag is contracted or tied at the center to form a bow and is connected with the head by a pin C.

Having described my invention, what I claim as new and original, and desire to secure by Letters Patent, is—

The design for a badge, as herein shown and described.

Signed at Providence, Rhode Island, this 8th day of June, 1901.

WILLIAM B. SHERMAN.

Witnesses:

GEO. H. REMINGTON,
JOHN T. HENTHORN.
